[57] CLAIM

The ornamental design for a illuminated pet collar and leash set, as shown.

DESCRIPTION

FIG. 1 is a front elevational view of the illuminated pet collar and leash set of the present invention;

FIG. 2 is a rear elevational view of the illuminated pet collar and leash set of FIG. 1;

FIG. 3 is a left side elevational view of the illuminated pet collar and leash set of FIG. 1;

FIG. 4 is a right side elevational view of the illuminated pet collar and leash set of FIG. 1;

FIG. 5 is a top plan view of the illuminated pet collar and leash set of FIG. 1; and,

FIG. 6 is a bottom plan view of the illuminated pet collar and leash set of FIG. 1.

The leash is shown broken away in FIGS. 1, 2, 5 and 6 to indicate indeterminate length.
